PAPER MAKING MACHINE

Filed Aug. 26, 1927

UNITED STATES PATENT OFFICE.

ARTHUR BELLEMARE, OF THREE RIVERS, QUEBEC, CANADA.

PAPER-MAKING MACHINE.

Application filed August 26, 1927, Serial No. 215,680, and in Canada October 19, 1926.

My invention relates particularly to paper making machines of the high speed type in which the paper during the process of manufacture is fed through a battery of dryer rolls at a speed of approximately a thousand feet per minute. These dryer rolls are disposed in staggered horizontal arrangement and their peripheries adjacent their front ends are grooved to accommodate endless ropes which are successively looped around the dryers and serve to facilitate the initial feeding of the paper therethrough.

One of the principal aims of modern development in the paper industry has been to increase the rate of production, and the speed of operation of the paper making machines has increased to such an extent that it is of vital importance that all possible precautions be taken to prevent the machines being put out of commission as heavy loss is incurred if a machine is rendered inoperative even for a short time.

One of the causes of breakdowns which have caused paper manufacturers considerable concern in the past has been the breakage of the ropes on the dryers hereinbefore referred to. These ropes, owing to their high speed of travel, have a tendency to jump from the grooves in which they normally run and when this occurs they at once become entangled in protruding parts on the machine frame or dryer heads and so tie-up the machine that it usually takes two or three hours to set the machine in operation again. The resultant loss will readily be appreciated when it is considered that the machine is capable of producing sixty thousand feet of paper per hour.

The present invention seeks to reduce these losses to a minimum by eliminating so far as possible the danger of breakage of the ropes in the event of their displacement from the dryer rolls.

To this end my invention consists of the combination construction and particular arrangement of the parts hereinafter described and illustrated and pointed out in the claims.

For full comprehension, however, of my invention reference must be had to the accompanying drawings in which similar reference characters indicate the same parts, and wherein:

Figure 1 is a diagrammatic front elevation of a part of a paper machine having my invention applied thereto;

Figure 2 is a transverse sectional view taken on line 2—2 Figure 3.

Figure 3 is a fragmentary front elevation drawn to a larger scale and illustrating the preferred arrangement of the guiding brackets.

Figure 4 is a sectional view of one of the guiding brackets illustrating its position relatively to an adjacent dryer roll;

Figure 5 is a sectional view taken on line 5—5 Figure 4; and

Figure 6 is a detail perspective view of one of the guiding brackets forming a part of my invention.

Referring to the accompanying drawings, the frame of the machine is indicated at 2, the dryer rolls at 3, the ropes by which the paper is initially fed through the dryers at 4, the paper, at the point at which it enters the "nip" of the ropes in the initial feeding operation, at 5, and the felt which passes around the dryers in unison with the paper at 6.

The dryers are of hollow cylindrical form with closed ends 7 and the interior of each constitutes a steam chamber with which a steam supply pipe not shown communicates. These dryers are arranged in two horizontal series located one above the other, with the dryers of one series staggered relatively to those of the other, and they are rotatably supported on horizontal shafts 8 which are journaled in bearings in the machine frame 2, suitable means being employed to drive the dryers at a uniform speed.

The ropes 4 are located at the "tending" side of the machine only and run in circumferential grooves 9 in the dryers and they are kept constantly under tension by a weighted sheave 10. These ropes are only used to start the paper through the dryers. In this initial feeding operation the width of the paper, as it moves towards the dryers, is reduced by a movable spray device until it is approximately but three inches, and the free end of this strip as it reaches the dryers is placed in what is known as the "nip" of the ropes and is carried by the latter successively around the dryers of the entire group, finally passing therefrom to the calendars (not shown). This initial travel completes the feeding operation so far as the ropes are concerned as the paper is subsequently fed by the frictional contact with the dryers and felt, this subsequent travel causing it to as-

sume its proper alignment and consequently leave the ropes so that the latter simply run idly in their grooves until they are again called upon to perform the initial feeding operation.

As hereinbefore pointed out these ropes, owing to their high rate of speed have a tendency to jump from the grooves, and as these grooves are located in close proximity to the adjacent end of the dryers the ropes slip off into the narrow space between the dryer heads and machine frame and become so entangled with the latter that breakage inevitably occurs before the machine can be stopped. The present invention seeks to prevent this by providing guiding means which will receive the ropes in the event of them jumping from their grooves and prevent them from becoming entangled with the frame or dryers, and which will facilitate the re-positioning of them in their respective grooves. To this end I mount a series of guide brackets 12 upon the machine frame adjacent each dryer head and arrange them in arcs conforming with those portions of the peripheries of the dryers that are in constant contact with the ropes as indicated in Figure 1, so that when the ropes become displaced they will simply run on the brackets and as the path they follow on the latter substantially conforms with that of the grooves they will not be subjected to any severe stresses or strains; and the machine can be stopped and the ropes replaced with little loss of time.

The brackets illustrated constitute the preferred embodiment of my invention but it is to be distinctly understood that the construction may be modified without departing from the spirit of the invention. For instance, one adjustable semi-circular bracket may be substituted for each series and still secure beneficial results.

In the illustrated embodiment each bracket is bolted to the machine frame as at 13 adjacent one end and extends therefrom to the adjacent dryer head and terminates in an upturned lip 14 which enters the usual recess 15 in the latter. The rope-engaging surface 16 of the bracket is curved concentrically to the periphery of the adjacent dryer and with the corresponding surfaces of the other brackets and has an upwardly projecting guard flange 17 which is constructed and arranged to prevent outward displacement of the ropes when on the brackets.

It will be seen from the foregoing that when a machine is equipped with these brackets the danger of breakage is almost eliminated, in fact breakage is not likely to occur unless the ropes are defective or become worn.

What I claim is as follows:

1. In a paper making machine, the combination of a rotary dryer roll having a

grooved periphery, a rope adapted to run in said groove, and means adapted to receive said rope when it becomes displaced from the groove, substantially as described.

2. In a paper making machine, the combination of a rotary dryer roll having a grooved periphery, a rope adapted to run in said groove, and a series of devices located in fixed position adjacent the dryer roll and arranged in an arc concentric to the periphery of the roll, said devices being adapted to receive the rope when it is displaced from its groove, substantially as described.

3. In a paper making machine, the combination of a plurality of dryer rolls, the periphery of each of which is grooved adjacent one end, ropes adapted to run in said grooves, and means located in position adjacent said end of each dryer roll and adapted to receive said ropes when they become displaced from the grooves, said means presenting a path for the ropes substantially the same as that presented by the grooves, substantially as described.

4. In a paper making machine, the combination of a plurality of dryer rolls, the periphery of each of which is grooved adjacent one end, ropes adapted to run in said grooves, and means located in position adjacent said grooved end of the dryer roll and adapted to receive said ropes when they become displaced from the grooves, said means consisting of a plurality of series of brackets, each series being arranged in an arc concentric with one of said rolls, substantially as described.

5. In a paper making machine, the combination of a rotary dryer roll having a grooved periphery, a rope adapted to run in said groove, and a bracket located in fixed position adjacent the dryer roll and adapted to receive said rope when it becomes displaced from said groove, said bracket having a rope-engaging surface curved concentrically with the periphery of said roll, substantially described.

6. In a paper making machine, the combination of a rotary dryer roll having a groove in its periphery adjacent one end, a rope adapted to run in said groove, and a bracket located in fixed position adjacent the said grooved end of the dryer roll and adapted to receive said rope when it becomes displaced from said groove, said bracket having a rope-engaging surface curved concentrically with the periphery of said roll and an upwardly projecting guard for preventing outward displacement of the rope when on said bracket, substantially as described.

7. In a paper making machine, the combination of a rotary dryer roll having a groove in its periphery adjacent one end thereof, a rope adapted to run in said groove, and means for limiting lateral dis-

- placement of the rope, substantially as described.
8. In a paper making machine, the combination of the frame thereof, a dryer roll 5 rotatably mounted in the frame and having a groove in its periphery adjacent one end thereof, a rope adapted to run in said groove, and a bracket mounted upon the frame for limiting lateral displacement of 10 the rope towards the frame.
9. In a paper machine, the combination of a rotary dryer roll having a groove in its periphery adjacent one end thereof, a rope adapted to run in said groove, and an angular bracket located in fixed position adjacent said rope, said bracket having a part 15
- disposed substantially parallel to the axis of the dryer roll and a second part disposed substantially perpendicularly thereto.
10. In a paper making machine, the combination of a rotary dryer roll having a groove in its periphery adjacent one end thereof, a rope adapted to run in said groove, and a bracket located in fixed position and having a substantially forked end 20 extending towards the rope for limiting outward displacement of the latter.

Signed at city of Three Rivers, Province of Quebec, this twenty-second day of August 1927.

ARTHUR BELLEMARE.
